CLAIM

The ornamental design for a hands free temperature gauge with laser indicator, as shown and described.

DESCRIPTION

FIG. 1 is a front left oblique view of a hands free temperature gauge with laser indicator showing my new design,
FIG. 2 is a front view thereof,
FIG. 3 is a back view thereof,
FIG. 4 is a left side view thereof,
FIG. 5 is a right side view thereof,
FIG. 6 is a top view thereof; and,
FIG. 7 is a bottom view thereof.
